Primary Examiner — Melanie Pellegrini(74) *Attorney, Agent, or Firm* — DLA Piper LLP (US)(57) **CLAIM**

The ornamental design for a wrist wearable device, as shown and described.

DESCRIPTION

FIG. 1 is a front, left, and top side perspective view of a wrist wearable device embodying the claimed design;
FIG. 2 is a rear, right, and bottom side perspective view thereof;

FIG. 3 is a front elevational view thereof;

FIG. 4 is a right side elevational view thereof;

FIG. 5 is a top plan view thereof; and,

FIG. 6 is a bottom plan view thereof.

The broken lines in the drawings represent portions of the wrist wearable device which form no part of the claimed design.
